(57) **CLAIM**

The ornamental design for a passenger vehicle wheel cover as shown and described.

DESCRIPTION

FIG. 1 is a perspective view of a passenger vehicle wheel cover mounted on a hub of a passenger vehicle showing our new design.

FIG. 2 is an isometric view thereof with an inner cover removed.

FIG. 3 is a back perspective view thereof.

FIG. 4 is a front view thereof with the inner cover removed.

FIG. 5 is a back view thereof.

FIG. 6 is a right side view thereof.

FIG. 7 is a left side view thereof.

FIG. 8 is a top view thereof; and,

FIG. 9 is a bottom view thereof.

The broken lines show environment and portions of the passenger vehicle wheel cover that form no part of the claimed design.

The shade lines in the Figures show contour and do not claim surface ornamentation or treatment.
